UNITED STATES PATENT OFFICE.

ANDREW ENRICO AND JOHN ENRICO, OF CHISHOLM, MINNESOTA.

RAILWAY-TIE AND RAIL-FASTENER.

1,299,442.

Specification of Letters Patent.

Patented Apr. 8, 1919.

Application filed June 20, 1918. Serial No. 240,954.

To all whom it may concern:

Be it known that we, ANDREW ENRICO and JOHN ENRICO, subjects of the King of Italy, residing at Chisholm, in the county of St. Louis and State of Minnesota, have invented 5 certain new and useful Improvements in Railway-Ties and Rail-Fasteners, of which the following is a specification.

The primary object of the invention is to 10 provide a railway tie adapted for securely locking rails in their operative positions thereon without the use or the employment of the usual railway spikes, the rails being easily and quickly released for removal 15 whenever desired.

A further object of the invention is the provision of rail securing means incorporated in a tie structure adapted for retaining the rails the proper distance apart upon 20 the tie, the holding members being automatically disengaged from the rails upon releasing the locking means which forms a part of the structure.

A still further object of the device is to 25 provide a combined tie and rail fastener that possesses great strength and utility and is easy and inexpensive to manufacture, the same having the advantages of securing the rails in position without the employment of 30 spikes and locking the rails against displacement until released by an authorized person having the proper key, it being impossible to release the rails in any other manner except by destroying a portion of the structure. 35

In the drawings forming a part of this application and in which like numerals refer to corresponding parts throughout the several views,

40 Figure 1 is a side elevation of the device with rails illustrated thereon in vertical transverse section;

Fig. 2 is a top plan view thereof;

45 Fig. 3 is a central vertical longitudinal sectional view of the same;

Figs. 4 and 5 are vertical transverse sectional views taken upon lines IV—IV and V—V respectively of Fig. 2;

50 Fig. 6 is a horizontal sectional view taken upon line VI—VI of Fig. 3;

Fig. 7 is a perspective view of one of the toggle locking members employed; and

Fig. 8 is a similar view of one of the rail-engaging fasteners.

My form of railway tie herein illustrated 55 is substantially the form of the usual tie adapted for transverse positioning upon the roadbed of the railway line, my tie however being preferably constructed of two superposed slabs or sections 10 and 11 secured together in tie formation by means of bolts 12. Railway rails 13 are adapted for seating transversely upon the upper face 14 of the top slab 11 with the outer flange 15 of each rail positioned beneath a jaw or fastener 16 60 secured to the said slab 11 spaced from the adjacent end of the tie.

A longitudinal recess 17 is provided centrally through the slab 11, the end walls 18 of said recess being beneath the rails 13 70 when positioned upon the tie. A movable jaw or fastener 19, having somewhat the shape of a railway spike is slidably positioned within the recess 17 having a flange form of head 20 overlying the inner base 75 flange 21 of the adjacently positioned rail 13.

Oppositely projecting feet 22 of the movable fasteners 19 are adapted for positioning within a well 23 formed in the lower slab 10 80 adjacent the opposite ends of the recess 17. The said recess 17 and well 23 are of sufficient width to permit the ready insertion of the fastener 19 with its feet 22 but the end portions 24 of the recess 17 are reduced in 85 width, forming opposite shoulders 25 beneath which the feet 22 are slidably positioned when the movable fasteners 19 are in their operative arrangement with the heads 20 thereof overlying the rail flanges 90 21 as best illustrated in Fig. 3 of the drawings.

A pair of toggle locking members 26 are adapted for positioning within the recess 17 for sliding beneath straps 27 carried by 95 the tie top 14 for spanning the said recess. Each of the locking members 26 consists of a lever portion 28 connected to a block 29 by means of a hinge 30. When the movable fasteners 19 are in place engaging the 100 rails 13, the locking members 26 are oppositely positioned within the recess 17 with the blocks 29 slidably positioned beneath the straps 27 and with the complementally formed free ends 31 of the levers 28 in interfitting engagement and adapted upon 105 forcibly depressing the engaged ends of the levers 28 to act after the manner of a toggle,

forcing the blocks 29 against the movable fasteners 19 and securely positioning the latter in place engaging the rails.

- One of the toggle levers 28 is provided 5 with a perforation 32 adapted for the reception of a locking pin 33 when both toggle levers are depressed and the perforation 32 is brought into alignment with similar perforations 34 provided transversely of the 10 slab 11. It will be apparent that the pin 33 locks the members 26 in position preventing the shifting of the fasteners 19 and retaining the rails 13 securely locked upon the tie. A suitable key-operated lock 35 may 15 also be provided for retaining the device assembled, the said lock having a bolt 36 adapted for projection into a keeper notch 37 in the side of the adjacently positioned toggle lever 28.
- 20 A spring 38 is positioned beneath each of the levers 28 for automatically elevating the said levers when the locking means is released while springs 39 are carried by the recess walls 18 bearing against the fasteners 25 19 for automatically moving the said fasteners inwardly out of engagement with the rail flanges 21 as well as longitudinally moving the locking members 26 inwardly when the levers 28 are released. It will be seen 30 that when the device is locked, the hinges 30 will be projectingly positioned beneath the straps 27 and that both the locking pin 33 and the bolt lock 35 may be employed if desired.
- 35 A keyhole slot 40 is arranged through the slab 11 for permitting the insertion of a proper key, not shown, into the lock 35 for shifting the bolt 36 thereof into and out of the keeper notch 37. The complete op- 40 eration of the device will be apparent from this detailed description of the manner of assembling the same, a releasing of the pin 33 and lock bolt 36 permitting the springs 38 to elevate the levers 28 and allowing the 45 springs 39 to move the entire toggle members 26 as well as the fasteners 19 inwardly so that the rails 13 being freed from the heads 20 may be removed from the tie at will. When the lock 35 is employed it will 50 be seen that only an authorized person having the proper key will be able to release the rails 13 in any manner excepting by breaking the heads 20 or jaws 16, while an authorized person may easily and quickly 55 lock the rails upon the tie or release the same from engagement therewith.

What I claim as new is:—

1. A tie and rail fastener comprising an elongated support having a longitudinal re- 60 cess therein adapted for the transverse seat- ing of rails thereon overlying the ends of the recess, movable fasteners for rails positioned adjacent the ends of said recess, toggle-locking means shiftably positioned with- 65 in the recess engaging the said fasteners, se-

curing means for the said locking members when depressed within the recess, inwardly shifting means for the fasteners, and elevating means for the locking members car- 70 ried by the support.

2. A tie and rail fastener comprising superposed slabs, with the upper slab having a central longitudinal recess therein, inwardly projecting jaws carried by the upper slab adjacent its opposite ends adapted for 75 overlying the adjacent bases of rails when transversely mounted upon the tie, the lower slab having wells therein beneath the opposite end portions of the recess forming opposite shoulders, movable fasteners within the opposite ends of the recess having heads adapted for overlying the inner base flanges of rails mounted upon the tie and also having oppositely projecting feet positioned beneath the said shoulders, toggle-locking 80 members for said movable fasteners operatively positioned within the recess, and springs carried by the end walls of the recess engaging said fasteners adapted for automatically moving the fasteners inwardly 85 out of engagement with the rails upon the retraction of said toggle-locking members.

3. A tie and rail fastener comprising superposed slabs, with the upper slab having a central longitudinal recess therein, 95 inwardly projecting jaws carried by the upper slab adjacent its opposite ends adapted for overlying the adjacent bases of rails when transversely mounted upon the tie, the lower slab having wells therein beneath the opposite end portions of the recess forming opposite shoulders, movable fasteners within the opposite ends of the recess having heads adapted for overlying the inner base flanges of rails mounted upon the tie, 100 and also having oppositely projecting feet positioned beneath the said shoulders, toggle-locking members for said movable fasteners operatively positioned within the recess, springs carried by the end walls of the 105 recess engaging said fasteners adapted for automatically moving the fasteners inwardly out of engagement with the rails upon the retraction of said toggle-locking members, a lock carried by the upper slab 110 having its bolt adapted to project within its recess, one of said locking members being provided with a keeper notch adapted for receiving the bolt of said lock when the locking members are in their depressed se- 115 curing arrangement, and springs in the lower slab beneath the toggle members adapted for automatically shifting said members when said lock is released.

4. A tie and rail fastener comprising superposed slabs, with the upper slab having a central longitudinal recess therein, inwardly projecting jaws carried by the upper slab adjacent its opposite ends adapted for overlying the adjacent bases of rails 120 125

when transversely mounted upon the tie, the lower slab having wells therein beneath the opposite end portions of the recess forming opposite shoulders, movable fasteners 5 within the opposite inner base flanges of rails mounted upon the tie and also having oppositely projecting feet positioned beneath the said shoulders, retracting means for said fasteners carried by the end walls 10 of the recess in normal engagement with the fasteners, straps upon the top of the tie spanning said recess, blocks slidably positioned within said recess beneath the straps in abutting engagement with said fasteners, 15 toggle levers hinged to the inner ends of said blocks having complementary interengaging free ends, whereby said levers are adapted to be depressed within said recess simultaneously with the upright shifting 20 movements of the blocks against said fasteners, and locking means for the said levers when depressed.

5. A tie and rail fastener comprising superposed slabs, with the upper slab having a central longitudinal recess therein, inwardly projecting jaws carried by the upper slab adjacent its opposite ends adapted for overlying the adjacent bases of rails when transversely mounted upon the tie, the 25 lower slab having wells therein beneath the opposite end portions of the recess forming 30

opposite shoulders, movable fasteners engaging the opposite inner base flanges of rails mounted upon the tie and also having oppositely projecting feet positioned beneath the said shoulders, retracting means for said fasteners carried by the end walls of the recess in normal engagement with the fasteners, straps upon the top of the tie spanning said recess, blocks slidably positioned within said recess beneath the straps in abutting engagement with said fasteners, toggle levers hinged to the inner ends of said blocks having complementary interengaging free ends, whereby said levers are adapted 40 to be depressed within said recess simultaneously with the lateral shifting movements of the blocks against said fasteners, a bolt lock carried by the upper slab adapted for securing engagement with one of said levers when depressed, and automatic elevating means for said levers carried by the lower slab beneath the levers adapted for automatically shifting the levers upwardly upon their hinges simultaneously with the inward releasing movement of said blocks and fasteners upon releasing the said lock. 45 50 55

In testimony whereof we affix our signatures.

ANDREW ENRICO.

JOHN ENRICO.
